UNITED STATES PATENT OFFICE

2,374,160

HATBOX

Heidi Marienthal, New York, N. Y.

Application September 1, 1944, Serial No. 552,253

1 Claim. (Cl. 206—8)

This invention relates to an article of manufacture, and specifically to a hatbox. Its main object is to provide a hatbox of the simplest possible construction, so as to save labor and material and also reduce its cost of manufacture to a minimum.

Another object of my invention is to provide a hatbox of transparent or translucent material, so that the hat may be visible from the outside.

A further object is to provide simple, easily manipulable means for simultaneously securing the box in the given shape and also for the attachment of a handle and keeping the lid in closed position.

With these and other objects in view, my invention consists in the construction, combination and arrangement of parts, as will be hereinafter described and defined in the appended claim.

In the accompanying drawing, which constitutes part of this specification, and in which similar reference characters denote corresponding parts:

Figure 1 is a top plan view of my box;
 Figure 2 is a side elevation thereof;
 Figure 3 a cross-section on line 3—3 of Figure 2;
 Figure 4 a cross-section on line 4—4 of Figure 1; and

Figure 5 a section on line 5—5 of Figure 2 seen in the direction of the arrows.

According to my invention, the hatbox comprises a side wall 10, a bottom 11 and a lid 12, all made of pliable transparent or translucent material. I prefer to use as such material what is commercially generally known as Lucite, because the same is obtainable in relatively thick sheets which can be readily bent or curved into any desired shape and which tend to retain their given shape. The side wall 10 is formed of a single sheet of said material by bending it into a cylindrical or polygonal shape, with the opposite end edges 10¹, 10² loosely overlapping one another, as indicated by dotted lines in Figure 2, and also shown in Figure 4. The bottom 11 is cut to conform in shape and width to the shape and the inner diameter of the said wall and is affixed to the latter by a plurality of pins or threaded bolts 13 distributed uniformly around the circumference of said wall, with some of said bolts being passed through the lower parts of the overlapping edges of said wall, as shown in Figure 2.

The upper part of the overlapping edges 10¹, 10² are adapted to be held in overlapped condition through means which simultaneously serve for the attachment of a handle 14 and for holding the lid 12 in closed position, as will be presently described. The handle 14 may consist of a leather belt or the like that for embellishment of

the box may be of a desired color and that is adapted to extend diametrically over the outer face of the lid 12. The lid 12 may be provided with a ruffled or otherwise ornamentally shaped 5 annular flange 12¹. The upper end of said side wall is provided with a pair of perforations 10a in each of the overlapping edges 10¹, 10², as well as with a pair of perforations in the diametrically opposite side of said wall. Coinciding with those 10 perforations 10a, 10a are perforations 12a, formed in the flange 12¹ of the lid, and perforations 14a, in the free ends of the handle 14. These perforations serve as passages for straps or ribbons 15 which may be looped through them from the 15 inside of said box and the free ends of which may be tied on the outside into bows or the like. These straps 15 thus at once secure the upper parts of the overlapped edges of the side wall in their condition and hold the lid in closed position, 20 and also serve as attachment means for the handle. For opening the box, the straps or ribbons on the side opposite the overlapping portions of the wall may be untied and the lid swung upwardly, the tied ends of the other strap or ribbon 15 acting as hinges.

It will be seen that the manufacture of the box, due to the construction above described, is thus rendered very simple, eliminating pasting or glueing and materials not readily available, while at 25 the same time lending the box an extremely neat appearance.

Since some modifications may be made in the construction without departing from the spirit of my invention, I do not wish to restrict myself to 30 the details described and shown.

What I claim is:

As an article of manufacture, a hatbox made wholly of pliable, transparent or translucent material, and composed of a side wall whose adjoining edges are loosely overlapping one another, a bottom mounted inside said wall, a plurality of 40 fastening elements between said bottom and said wall distributed around the circumference of the latter and some of which are passed through said 45 overlapping edges to hold the wall in shape, a flanged lid, a handle of flexible material extending diametrically over said lid, the said wall both in its overlapped edges and in the diametrically opposite side thereof, the flange of said lid and the free ends of said handle being perforated at corresponding points, and flexible means adapted to be looped through said perforations so as to simultaneously join the upper parts of said overlapping edges together, secure said handle and 50 hold the lid in closed position.

HEIDI MARIENTHAL.
